UNITED STATES PATENT OFFICE.

WARREN W. CARPENTER OF NEWARK, NEW JERSEY, ASSIGNOR, BY MESNE ASSIGNMENTS, TO WESTERN ELECTRIC COMPANY, INCORPORATED, A CORPORATION OF NEW YORK,

TELEPHONE-EXCHANGE SYSTEM.

1,251,637.

Specification of Letters Patent.

Patented Jan. 1, 1918.

Application filed October 21, 1915. Serial No. 57,070.

To all whom it may concern:

Be it known that I, WARREN W. CARPENTER, a citizen of the United States, residing at Newark, in the county of Essex and State 5 of New Jersey, have invented certain new and useful Improvements in Telephone-Exchange Systems, of which the following is a full, clear, concise, and exact description.

This invention relates to telephone exchange systems, and particularly to a register relay circuit for use in telephone exchange systems of the semi-automatic type.

The object of the invention is the provision of a register relay circuit having a minimum number of relays therein, and capable of registering or storing up any number corresponding to any possible combination of keys depressed by the operator.

In the drawings, Figures 1 and 2 illustrate, the invention as applied to a telephone system, with so much of the system illustrated as is necessary for an understanding of the invention.

The invention is adapted to be used in connection with a semi-automatic telephone system such as shown and described in Patent No. 1,168,319, granted to A. E. Lundell for improvements in automatic telephone exchange systems.

It is desirable in semi-automatic telephone systems to have a keyboard at an operator's position, which is adapted for temporary connection with a plurality of sending apparatus. To obtain the best results 35 from such an arrangement, there is provided a register relay circuit for each sending apparatus, which circuit is provided with means for registering or storing up the number of the substation set up by the operator 40 on her keyboard, and after such registration, the keys are released for use in connection with a subsequent call on another sending apparatus, without waiting for the completion of the sending operation on the preceding call.

The keyboard is diagrammatically shown in Fig. 2, and comprises four rows of keys of ten keys each, though more or less rows may be provided depending on the size of 50 the system in which they are to be used.

The various keys, when depressed, are held in their depressed position (by means not shown) until the energization of the release magnets 200, when they return to their normal position.

The register relay circuit is diagrammatically shown in Fig. 1, and includes relays 100—113, inclusive, arranged in a plurality of series 100—102, 103—105, 106—109, 110—113, as shown, each relay having an energizing winding and a locking or holding winding, as well as two armatures. Each of the series above enumerated has associated therewith one of the cut-out relays 114, 115, 116 or 117, for a purpose to be hereinafter 60 described. This register relay circuit governs the operation of the switch controlling or counting relay circuit to which it is shown connected. The depression of a plurality of keys to represent a line number results in the 70 energization of a group of register relays, one or more, or none, of the relays of each series being selected to form the group. Further, one or more of the cut-out relays 114, 115, 116, 117 may be energized in combination with the group. When energized, the relays in the selected group are locked up by a circuit including their locking windings, so that the number represented by the 75 depressed keys is registered or stored up, permitting the depressed keys to be released for use in connection with a subsequent call on another sending apparatus. The sending operation may now take place, the counting relay circuit being governed by the lock-up 80 group of register relays to send the necessary series of impulses to connect with the desired line.

The operation of setting up and registering the number of a called subscriber and the 90 subsequent control of the counting relay circuit will now be described in detail, as by following such operation it is thought the invention can be most readily understood.

A subscriber, wishing to talk with any 95 other subscriber of the system, communicates, in the usual manner, the number of such wanted subscriber to the operator at the central office. It will be assumed that the number of such wanted subscriber is 100

7180. The operator on receiving such number depresses the No. 7 key in the 1000's row of keys, the No. 1 key in the 100's row, the No. 8 key in the 10's row and the 5 No. 0 key in the unit's row. The depression of these keys causes the closing of the following circuits: battery, sequence switch contact spring 118, conductor 119, sequence switch contact spring 120, conductor 121, 10 energizing winding of register relay 100, conductor 122, the No. 7 key in the 1000's row, to ground; battery, sequence switch contact spring 118, conductor 119, sequence switch contact spring 120, conductor 123, energizing 15 winding of register relay 101, conductor 124, the No. 7 key in the 1000's row, to ground; battery, sequence switch contact spring 118, conductor 119, sequence switch contact spring 125, conductor 126, energizing winding 20 of register relay 103, conductor 127, the No. 1 key in the 100's row, to ground; battery, sequence switch contact spring 118, conductor 119, sequence switch contact spring 128, energizing winding 25 of register relay 109, conductor 130, the No. 8 key in the 10's row, to ground; battery, sequence switch contact spring 118, conductor 119, sequence switch contact spring 128, conductor 131, energizing winding of cut-out relay 116, 30 conductor 132, the No. 8 key in the 10's row, to ground; battery, sequence switch contact spring 118, conductor 119, sequence switch contact spring 133, conductor 134, energizing winding of cut-out relay 117, conductor 35 135, the No. 0 key in the unit's row, to ground. The closure of the circuits for the relays 100, 101, 103, 109, 116, 117 causes the energization of said relays and the consequent attraction of their armatures, the 40 relays at their right armatures and front contacts completing break points in locking circuits which, when completed, extend from battery, sequence switch contact spring 136, over the conductors 137, 138, 139, 140 and 45 141, through the locking windings of the energized relays to ground.

Each row of keys has associated therewith a key 201 which is depressed whenever a key in the row is depressed. When the 50 last key of a group of keys representing the 1000's, 100's, 10's and units digits of the wanted line is depressed, a circuit is closed from battery, motor magnet of sender sequence switch 142, conductor 143, lower and 55 upper contacts of sequence switch contact spring 144, the closed keys 201 in series to ground, moving the sequence switch from position 3 to position 4. As the sequence switch comes into position 3₁, the locking circuit above traced is closed at the upper right contact of sequence switch contact spring 136, maintaining the armatures of the energized relays in their attracted position. On the sequence switch coming into

position 4 and until it leaves position 4₁, 65 circuits are closed at upper right and left contacts of sequence switch contact spring 145 to energize the release magnets 200, allowing the depressed keys to return to normal. In position 4 of sequence switch 70 142, a circuit is closed from battery, motor magnet of sequence switch 142, conductor 143, conductor 146, upper right contact of sequence switch contact spring 147, conductor 148, right armature and back contact of allotter relay 149, conductor 150, upper left contact of allotter sequence switch contact spring 151, to ground, moving sequence switch 142 from position 4 to position 5. If a depressed key, for any reason, 75 does not return to normal upon the energization of the corresponding release magnet 200, the circuit for the allotter relay 149 remains closed, preventing the sequence switch 142 from passing out of position 4. The 80 allotter relay 149 is initially energized in series with all of the operated register relays when the keys are depressed, and hence it remains energized as long as any of the keys remain in their operated positions. 85 With the allotter in position 1, and when the sequence switch 142 reaches position 3₁ the following circuits are established for the relay 149: from battery, relay 149, allotter contact in position 1, contact 118 90 (positions 3₁ to 4), and thence in parallel through contacts 118, 133, 131, 125 in positions 3₁ to 4, through the energized registering relays to ground at the contacts of the operated keys. If all of these keys are restored, all of these branch circuits are interrupted, and the relay 149 is released. The operator observing that the call is held up, releases the depressed key, thus destroying the circuit for allotter relay 149 which 95 allows its arms to retract, completing the circuit to move sequence switch 142 from position 4 to position 5, as above described. This holding up of a call until all the keys are returned to normal, prevents a possible 100 mistake in a subsequent call.

When the sequence switch 142 reaches position 5, the fundamental circuit is completed from grounded battery, relay 212 at the district selector, through suitable contacts not shown, but similar to those employed in the system disclosed in Patent No. 1,168,319, conductor 213, winding of stepping relay 152, sequence switch contact 214, conductor 215, to ground at the armature and back contact of the 0' relay. Relays 212 and 152 are energized in this circuit, relay 212 functioning as described in the mentioned patent to cause the district selector switch to start upon its first selecting movement.

The energization of stepping relay 152 completes a circuit from battery, conductor

153, the No. 3 counting relay, armature and back contact of No. 3' counting relay, conductor 154, left armature and front contact of register relay 101, conductor 155, left armature and back contact of register relay 102, conductor 156, upper left contact of sequence switch contact spring 157, conductor 158, lower right contact of sequence switch contact spring 159, armature and front contact of stepping relay 152, to ground, energizing the No. 3 counting relay and resulting in the sending of four impulses to cause brush selection. As the district selector moves upward, the commutator diagrammatically indicated at 216 causes the intermittent shunting of stepping relay 152 upon the completion of each group step. This operation of stepping relay 152 causes the counting relays to be successively energized in the well-known manner. When the 0' counting relay is energized, the lower branch of the fundamental circuit is opened, and when the brushes are centered, relay 212 deenergizes to accomplish the proper sequence of operations at the district selector. The energization of the 0' counting relay also completed a circuit from grounded battery, power magnet of sequence switch 142, sequence switch contact 217, conductor 218, to ground at the armature and front contact of the 0' counting relay. Sequence switch 142 then moves from position 5 to position 7. After brush selection, the sender sequence switch 142 moves into position 7, where group selection takes place, the circuit for the proper counting relay being closed from battery, conductor 153, the No. 3 counting relay, conductor 154, left armature and front contact of register relay 100, upper left contact of sequence switch contact spring 160, conductors 161, 158, lower right contact of sequence switch contact spring 159, armature and front contact of stepping relay 152 to ground, again resulting in the energization of the No. 3 counting relay. It will be observed, however, that the register relay 103 is energized in combination with the register relay 100. As soon as the No. 3 counting relay is energized, the No. 3' counting relay is also energized over a local circuit closed at the armature and contact of the No. 3 counting relay. The No. 3' counting relay when operated extends the conductor 154 through to the No. 2 counting relay which is, therefore, energized upon the next energization of the stepping relay 152. In response to the operation of the No. 2 counting relay the No. 2' counting relay is energized. The No. 2' counting relay, however, instead of extending the conductor 154 to the No. 1 counting relay extends such conductor to the No. 0 counting relay, owing to the fact that the register relay 103 has been operated. Therefore, upon the next or third energization of the stepping magnet 65 152, the following circuit is established for the No. 0 counting relay: from battery, the No. 0 counting relay, conductor 165, front contact and left armature of relay 103, contact 168 (position 7), conductor 162, front 70 contact and armature of the No. 2' counting relay, front contact and armature of the No. 3' counting relay, conductor 154, front contact and lefthand armature of the relay 100, contact 160 (position 7), conductor 161, conductor 158, contact 159 (position 7), armature and contact of the stepping relay 152 to ground. From the above it is apparent that although the No. 3 counting relay is energized, the No. 0 counting relay is operated after three operations of the relay 152 instead of after four as in the first case assumed, due to the fact that one pair of counting relays, 1 and 1' is skipped, due to the operation of the relay 103. When the 80 0' counting relay is energized, it again opens the lower branch of the fundamental circuit and allows relay 212 to deenergize, such relay 212 thereupon causing the necessary operations of the district selector switch. At 85 the same time a circuit is completed for moving sequence switch 142 out of position 7 and into position 9. With the sequence switch 142 in position 9, where final brush selection takes place, a circuit for the proper counting relay being closed from battery, conductor 153, the No. 1 counting relay, armature and back contact of No. 1' counting relay, conductor 166, left armature and back contact of cut-out relay 115, lower left contact of sequence switch contact spring 163, conductors 162, 167, left armatures and back contacts of register relay 104 and register relay 105, upper left contact of sequence switch contact spring 168, conductor 100 158, lower right contact of sequence switch contact spring 159, armature and front contact of stepping relay 152 to ground, causing the sending of two impulses. It is to be understood that in this operation the stepping relay is controlled by a commutator at a switch to which the district selector has established connection, this being accomplished in a manner set forth in the previously mentioned patent. The sequence switch 142 now moves into position 11 for final tens selection, in which position a circuit is closed from battery, No. 9 counting relay, conductor 169, left armature and front contact of register relay 109, conductor 170, upper left and lower right contacts of sequence switch contact spring 159, armature and front contact of stepping relay 152, to ground. The counting relay circuit now 105 115 "runs down" until the No. 2' relay is energized, when a circuit is closed through conductor 162, lower left contact of sequence switch contact spring 171, left armature and 120 125

front contact of cut-out relay 116, conductor 165 to the No. 0 counting relay, thus cutting out the Nos. 1 and 1' counting relays and allowing but nine impulses to be sent instead of ten impulses, as would be the case if the counting relay circuit were to "run down" in the usual manner. The sequence switch 142 now moves into position 13 to cause units selection, in which position a circuit is closed from battery, conductor 158, the No. 0 counting relay, conductor 165, left armature and front contact of cut-out relay 117, lower left contact of sequence switch contact spring 172, conductor 162, the back contacts and left armatures of the register relays 110, 111, 112 and 113 in series, lower left and right contact of sequence switch contact spring 159, armature and front contact of stepping relay 152 to ground, allowing one impulse to be sent to cause units selection. Units selection having taken place, the register relay circuit is released, but as any further operation of the register relay circuit forms no part of the invention it will not be described.

What is claimed is:

1. A series of counting relays normally operating in sequence to transmit a number of impulses in succession, the number of impulses sent ordinarily depending upon the position of the counting relay of the series first operated, in combination with a register relay circuit having a plurality of relays therein arranged in series, said register relay circuit under certain conditions causing the normal operation of said series of counting relays, whereby the number of impulses sent corresponds to the position of the relay of the series first operated, and under certain other conditions causing the number of impulses sent to be less than the number corresponding to the position of the relay of the series first operated.

2. In a semi-automatic telephone system, the combination with keys adapted to be set by the operator in combinations to represent any line number of the system, of a register relay circuit associated with said keys and having a plurality of series of relays therein, said relays being selectively operable in predetermined groups corresponding to the combinations of keys set up by the operator, a series of counting relays governed by the setting of said register relays, and means associated with said register relays for eliminating one pair of counting relays whereby a less number of impulses will be sent than ordinarily.

3. In a semi-automatic telephone system, an operator's sending device including a group of register relays, a manually operated device governing the operation of such relays, a counting device, means controlled by said register relays for initially deter-

mining the extent of the counting operation of said counting device, and an additional relay governed by certain of said manually operable devices for subsequently modifying the counting operation of such counting device.

4. In a controlling device for semi-automatic telephone systems, a plurality of relays arranged in groups, manually operable keys for controlling the operation of said relays, a series of counting relays governed in its operation by said plurality of relays, means associated with said plurality of relays under certain conditions for altering the operation of said series of counting relays as determined by said keys.

5. In a semi-automatic telephone system, an operator's sending device comprising a plurality of series of register relays, a cut-out relay associated with each series of register relays, a keyboard having a plurality of series of keys corresponding in number to the series of register relays and adapted to be depressed by the operator in combinations to represent any line number of the system, said combination of keys when depressed energizing a predetermined group of register relays and under certain conditions one of said cut-out relays, a switch-controlling means governed in its operation by said register relays, said control by the register relays being altered when one of said cut-out relays are energized.

6. In a semi-automatic telephone system, an operator's sending device comprising a plurality of series of register relays, a cut-out relay associated with each series of register relays, a keyboard having a plurality of series of keys corresponding in number to the series of register relays and adapted to be depressed by the operator in combination to represent any line number of the system, said combination of keys when depressed energizing a predetermined group of register relays and under certain conditions a plurality of said cut-out relays, a switch-controlling means governed in its operation by said register relays, said control by the register relays being altered when a plurality of said cut-out relays are energized.

7. In a semi-automatic telephone system, an automatic switch, a sending device for controlling the operation of such switch and including a counting device adapted to count one step in a definite series of steps for each step of the switch under control and to stop such switch when the last step in the series is counted, manually controlled means for determining the position of the first step in the series to be counted, and manually controlled means for eliminating an intermediate step in the series counted.

8. In a semi-automatic telephone system, an automatic switch, a sending device for

controlling the operation of such switch and including a counting device adapted to count one step in a definite series of steps for each step of the switch under control and to stop 5 such switch when the last step in the series is counted, a pair of keys either one of which is adapted, when operated, to determine the

same initial step in the series, and one of which is adapted to eliminate a subsequent step in the same series.

In witness whereof, I hereunto subscribe my name this 19th day of October, A. D. 1915.

WARREN W. CARPENTER.
